SLIP

Arthur M. Thomas, Mendham, N. J., assignor to
 Thomas & Marcus, Inc., New York, N. Y., a corporation of New York

Application March 14, 1936, Serial No. 68,828

3 Claims. (CL 2—73)

This invention relates to slips, and has for an object to provide an improved construction presenting a full skirt with a brassière attached to the front with the parts so arranged as to expose 5 almost the entire back from the waistline to the top of the body.

Another object of the invention is to provide a slip wherein the skirt extends to the waistline at the back and at the front above the waistline so 10 that a brassière may be connected therewith at the front and at the same time the rear may be left almost completely open.

An additional object, more specifically, is to provide a slip which will expose almost fully the 15 back from the waistline upwardly and also expose part of the sides below the waistline.

A further and still more specific object of the invention is to provide a slip with a full back exposure at the top and with a double thickness of 20 fabric between the crotch and the waistline with certain of the parts arranged to act as panties.

In the accompanying drawings:

Fig. 1 is a perspective view of a slip disclosing an embodiment of the invention, the same being 25 illustrated on a figure;

Fig. 2 is an enlarged rear view of the slip shown in Fig. 1;

Fig. 3 is a rear perspective view of the upper 30 part of the figure and slip shown in Fig. 1;

Fig. 4 is a view similar to Fig. 2 but disclosing a modified construction;

Fig. 5 is a vertical sectional view through Fig. 4 approximately on the line 5—5;

Fig. 6 is a transverse sectional view through 35 Fig. 5 approximately on the line 6—6;

Fig. 7 is a detail fragmentary sectional view through Fig. 4 on the line 7—7;

Fig. 8 is a detail fragmentary horizontal sectional view through Fig. 5 approximately on the 40 line 8—8.

Referring to the accompanying drawings by numerals, 1 indicates the skirt which extends preferably from below the knee to the waistline in the back and to a point above the waistline in the 45 front. As illustrated particularly in Figs. 1 and 2, the front is provided with an A-shaped extension 2 while the back is provided with a puckered portion 3 connected to an elastic band 4 which has its ends connected at 5 and 6 to the front part of the skirt at the waistline. When in use the elastic band 4 is intended to be placed directly on the 50 waistline.

The brassière 7 is connected to the upper edge 55 of the front A-shaped extension 2 and has secured at the upper part thereof the respective

ends of the shoulder straps 8 and 9, which shoulder straps at the rear are connected to an elastic strap 10. Strap 10 has one end stitched or otherwise rigidly secured at 11 to one edge of the center of the brassière, while the opposite end is disengageably connected by any suitable means, as for instance a hook and eye, to the opposite edge 12 of the brassière. This arrangement causes the elastic strap 10 to act on the breast pockets 13 and 14 to give them a circumferential tension, while 10 the straps 8 and 9 act to support or uplift these pockets.

The lower edges of the respective pockets 13 and 14 merge into the side edges 15 and 16 of the skirt 1, and said side edges extend downwardly to 15 from what may be termed hip notches or openings 17 and 18 which extend toward the hip line. By this construction and arrangement the garment, when viewed from the front as shown in Fig. 1, presents deep notches at the sides on the 20 waistline but with the notches appearing to extend upwardly and downwardly from the waistline. However, the part above the waistline consists only of the brassière with its supporting and retaining members so that the back is almost completely exposed from the waistline upwardly as 25 shown in Fig. 3. In addition, part of the sides above the hips are exposed.

As shown in Figs. 4 to 8, the slip is of identical construction to that shown in Figs. 1 to 3 inclusive, except for certain modified parts, and consequently the same numbers will be used except for the modified features. The modified construction forms what may be termed panties 30 19. These panties are formed from front and rear panels 20 and 21 which are connected together and to the sides of skirt 1 by suitable lines of stitching 22 and 23 from the bottom of the notches 17 and 18 to the points 24 and 25. The upper edge of the panel 21 is connected 35 by stitches to the respective edges 26 and 27 to the top of the rear of the skirt and by suitable lines of stitching to the center part of the band 4. The front panel 20 is connected by suitable lines of stitching to the side edges 28 and 29 of 40 the A-shaped extension 2 and connected to the top of this A-shaped extension by the lines of stitching 30 and 31. From the construction just described it will be seen that the garment is of double thickness from a line drawn through 45 points 24 and 25 to the top of the A-shaped extension 2. Both the front and rear panels taper from the points 24 and 25 as indicated by the dotted lines 32 and 33 so as to provide leg openings 34 and 35 and a connecting crotch 50 55

formation 36. This crotch strap or formation may be provided with hooks and eyes or other disengageable fastening means.

Preferably when the garment is donned the 5 hooks and eyes for the crotch strap are engaged and the garment is then drawn upwardly over the feet and legs until the strap 10 reaches the waistline. The brassière 7 and the associated straps are then placed in correct position. The 10 garment then will appear as shown in Figs. 1 and 2. Preferably the panels 20 and 21 are made from the same material as the skirt 1, and consequently, if desired, the waste produced by cutting along lines 32 and 33 may be used for the 15 respective panels 37 and 38 on the bottom of the skirt as shown in Figs. 4 and 5.

I claim:

1. A slip comprising a brassière, a skirt having its rear extending from the bottom of the slip 20 to the waistline and its front from the bottom of the slip to the lower edge of the brassière, the portion of the skirt at the sides connecting the front and rear being notched downwardly in a substantially V-shaped formation from the 25 waistline, and an elastic band extending across said notches having its center part connected to the center upper edge of said rear and its ends to the front forwardly of the sides of the slip.
2. A slip comprising a brassière, a skirt at the 30 rear extending upwardly to the waistline and at the front extending past the waistline to the brassière, means for connecting the front to the

brassière, the sides of the skirt being notched downwardly from the waistline towards the hip line, an elastic band having its center portion connected to the center portion of the upper edge of said rear and its ends to the front at the 5 waistline, a substantially tubular panty having its upper end conforming in shape to the upper end of said skirt, and seams connecting the upper edges of said panty to the upper edges of said skirt, said panty at its lower part tapering to form a crotch strap, the tapering portions being open whereby leg openings are presented.

3. A slip including a skirt extending at the back to the waistline and at the front to a point above the waistline, said skirt being formed with 15 circumferentially extending notches at the front, said notches straddling the waistline so that the front of the slip at the waistline will be of less width circumferentially than the front of a person wearing the slip, said skirt also being formed with a notch at each side with the bases of the notches positioned to extend circumferentially at the waistline, said notches having their apices appreciably below the waistline and positioned to point downwardly, and an elastic strap having 20 its center connected to the upper edge of said back, said strap extending across the bases of said last mentioned notches, the ends of said straps being connected to that part of the front which extends above the waistline whereby the 25 center of said back is retained in an elevated position.

ARTHUR M. THOMAS.
